(57) **CLAIM**

I claim the ornamental design for a cutting blade, as shown and described.

DESCRIPTION

FIG. 1 is a front perspective view of a cutting blade with the cutting edge shown broken away to indicate indeterminate length.

FIG. 2 is a front view of the cutting blade shown in FIG. 1.

FIG. 3 is a top view of the cutting blade shown in FIG. 1.

FIG. 4 is a bottom view of the cutting blade shown in FIG. 1.

FIG. 5 is a rear view of the cutting blade shown in FIG. 1.

FIG. 6 is a right side view of the cutting blade shown in FIG. 1; and,

FIG. 7 is a left side view of the cutting blade shown in FIG. 1. The present application is directed to independent features of the shape and contour of the design illustrated in the drawings. The broken line showing of the cutting tool is included for the purpose of illustrating portions of the cutting tool and forms no part of the claimed design.
